UNITED STATES PATENT OFFICE.

GEORGE W. O'KEEFE, OF DORCHESTER, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

ELECTRIC SWITCH.

Application filed December 21, 1922. Serial No. 608,302.

- This invention relates to electric switches adapted to control small motors and the like, and has particular reference to electrically operated switches.
- 5 An electrically operated switch may include an actuating coil which is adapted to effect the closing and opening of the switch and said coil may be governed by remotely disposed control switches.
- 10 It is an object of this invention to provide an electrically operated switch with means by which the switch may also be controlled manually upon failure of the actuating coil to operate, or for other purposes.
- 15 A further object is to provide switch operating mechanism and an actuating coil therefor adapted to be energized to operate the mechanism and close the switch and hold the switch closed for so long as the coil is energized; and said mechanism is or may be so arranged that it may be operated manually and locked in switch closed position and released manually to provide a rapid opening of the switch. Said operating 20 mechanism may further be so arranged that if set manually into switch-closed position and the actuating coil becomes energized, the mechanism will become unset and biased towards switch-open position in readiness to 25 open the switch when the actuating coil is de-energized.
- A further object is to provide improved means governed by an overload to de-energize the actuating coil and effect the opening 30 of the switch.
- A further object is generally to improve the construction and operation of electric switches.
- The switch embodying the invention may 35 include a stationary switch member and a movable switch member. The switch operating mechanism may include an actuating electro-magnet and a toggle operated by the armature of the electro-magnet to actuate the movable switch member. Said toggle and armature are or may be so arranged that the toggle is not locked in straightened position when the armature is actuated by the energization of the actuating coil; and the switch member may consequently move to open position when the actuating coil is de-energized. Said toggle, however, is or may be arranged to be moved to an over-shot or set position manually whereby releasably to hold the switch closed and is or may be arranged to be unset manually whereby to effect the opening movement of the movable switch member when the actuating coil is out of service. The armature of the actuating coil is or may be also arranged to unset 55 the toggle in the switch-closed position of the armature, if the switch has been set manually, whereby when said coil is de-energized, the switch will move to open position.
- Fig. 1 is a front elevation of an electric 60 switch embodying my invention with a portion of the enclosing casing broken away to illustrate the mechanism.
- Fig. 2 is a plan view of Fig. 1 with a cover 65 of the switch removed.
- Fig. 3 is a section along line 3-3 of Fig. 4.
- Fig. 4 is an end view of the switch with the side wall of the enclosing casing broken away to illustrate the overload coils.
- Fig. 5 is a detail illustrating the switch 70 operating mechanism.
- Fig. 6 is an end view of the actuating coil.
- Fig. 7 is a section along the line 7-7 of Fig. 5.
- Fig. 8 is a diagram illustrating the circuit connections between the switch and the actuating coil.
- Fig. 9 is a sectional detail illustrating the 75 method of securing a movable switch member to the insulating operating bar.
- Fig. 10 is a plan view of a retaining plate for the operating shaft.
- Fig. 11 is a perspective view of the over- 80 load coil supporting frame.
- Fig. 12 is a section along line 12-12 of Fig. 11.
- Fig. 13 is a perspective view of a knock-out plate.
- As here shown, the switch embodying the 85 invention may comprise a casing including the upper casing portion 10 which may have the reflexed strips 11 secured to the rear wall thereof, whereby to provide means for securing the switch to a support. Said casing portion 10 may be provided with a cover which may include the cover portion 12 which is adapted to be fixed more or less permanently to said casing end, and the com-

plementary cover portion 13 which is adapted to complete the closure of said casing portion 10. Said cover portion 13 may be locked removably to the casing 10 by any suitable means as, for instance, the lock member 14. The casing also includes the oil receptacle 15 which is received within and depends below the side walls of the upper casing portion 10.

10 Said receptacle is adapted to contain oil in which the switch members and the tripping coils are immersed. An insulating plate 16 of suitable material, as slate or porcelain, is received within the upper casing portion 10 and is adapted to form a cover for the major portion of the oil receptacle. Said insulating plate may be secured to the casing in any suitable manner, as, for instance, ears 17 may be reflexed inwardly from the lower edge of the casing 10 and serve as supports to which said insulating plate is secured. Said insulating plate is adapted to support the movable and stationary switch members. The switch terminals and circuit leads are adapted to be contained in the casing above said insulating plate, and the switch members below said insulating plate.

The switch here shown is adapted for the control of a three phase electric circuit and, consequently, is or may be provided with three movable and stationary switch members. The number of switch members may be varied, however, to suit the requirements of any particular circuit to be controlled.

15 The movable switch members are or may be identical in construction. Each movable switch member may include a U-shaped bracket 20 which depends below the insulating plate 16. Said bracket may be secured to said insulating plate by suitable means as the bolt 21 which has an enlarged head 22 received between the arms of said bracket. Said bolt may be extended through said plate and a nut 23 may clamp the bolt and the bracket in position. A terminal lug 24 may also be secured to said bolt and may receive a circuit lead which may be extended into the top compartment of the casing through suitable apertures in the side walls 50 of the casing. For conveniently introducing the circuit leads into the switch casing, said casing may be formed with apertures through the walls thereof; and said apertures may be covered by knock-out plates 24^a which may be secured, preferably removably, to said walls over the apertures by the screws 24^b. Said plates are or may be formed with knock-out portions 24^c in a more or less customary manner; and said portions 24^c are 55 preferably smaller than the apertures in the walls of the casing. This arrangement provides means whereby two sizes of conduits may be secured to the casing. The small conduit may be received in the aperture in 60 the knock-out plate formed by removing the

knock-out portion 24^c and the large conduit may be received in the aperture in the casing wall, the plate 24^a being removed for this purpose.

The movable switch member may include 70 the U-shaped or channel brush holder 25, the up-turned arms of which are pivoted on the pin 26, which latter is or may be extended through the lower end of the arms of the bracket 20. A conducting and supporting 75 strip 27 is received in said brush holder and extended forwardly therebeyond. A second conducting strip 28 is also received in said brush member above said first conducting strip 27 and is provided with a detachable 80 contact member 29 on its forward end. A brush member 30 is superimposed on said conducting member 28 and forms the main movable current carrying member of the switch. Said brush member and strips 27 85 and 28 are secured to said brush holder by suitable means as the screws 31. Said brush member is connected electrically to the bolt 21 by means of the flexible braid 32 which is clamped to the brush member 30 by said 90 screw 31 and is or may be soldered to the enlarged head 22 of said bolt 21. The movable switch members, as so far described, are or may be identical. A bar 33 of suitable 95 insulating material as wood is secured to the brush holders 25 whereby to operate them conjointly. Said securing means may be as illustrated in Fig. 9 wherein each screw 31 may pass through said bar 33 into a recess 34 sunk in the upper face of said bar 33 and a nut 35 may be threaded on the upper end of said screw 31. A bracket 37 may be secured to the middle portion of said bar 33 and a connecting rod 38 may be pivotally 100 connected therewith. Said rod may extend upwardly through a slot in said insulating plate 16 and may be pivotally connected with an arm 39 which is laterally extended from and secured to an operating shaft 40. Said operating shaft may extend transversely across the upper portion of the casing 10 and may be journaled in the rear wall of the casing and extend upwardly beyond and be journaled in the bottom of a slot 41 105 formed in the front wall and extended downwardly from the top edge of said wall. A shaft-retaining plate 42 may be secured removably to the outer face of the front wall of said casing 10 over the slot therein by suitable means as the bolts 43; and the lower edge of said plate may be formed or provided with a recess 44 (Fig. 10) which extends upwardly from the lower edge thereof and in which said operating shaft 40 is received. This arrangement provides means whereby said operating shaft is secured positively in position and yet may be removed when desired upon removing said plate 42.

A compression spring 46 may be disposed to encircle the lower portion of said connect-

ing rod 28 and press against said insulating plate 16 whereby to bias the switch toward open position.

The stationary switch members are or may be identical in construction. Each member may comprise a strip or plate 59 of conducting material having the reflexed foot 51 which is secured to the lower face of the insulating plate 16 by suitable means as 10 the bolt 52. Said bolt is adapted to be electrically connected with said conducting strip 50 and pass through said insulating plate and form a terminal member of the switch. The middle stationary switch member may 15 be provided with a terminal lug 53 by which connection may be made with one wire of the motor or other circuit to be controlled. The outer switch members are adapted to be connected with overload or tripping coils 20 as will hereinafter be described. Separate contact members for the brush member and contact member of the movable switch member are or may be secured detachably to the stationary contact members. Said contact 25 members may be of similar construction and may comprise L-shaped members 55 and 56 which are disposed upon opposite sides of the stationary switch member and are or may be secured to said member by the bolt 30 57. Said contact member 55 is adapted to be engaged by the brush member 30 and said contact member 56 is adapted to be engaged by the movable contact member 29. Said contact members 55 and 56 are, preferably 35 detachably connected with the stationary switch member and may be removed and replaced by other contact members when worn by use.

The outer stationary switch members are 40 or may be provided with L-shaped attaching members 58 and 59 to which terminals of separate overload tripping coils are adapted to be connected. Similar L-shaped attaching members 60 and 61 are secured to the 45 lower face of said insulating plate 16 by suitable means as the bolts 62 and 63 and are adapted to be connected with separate terminals of the overload coils. Said bolts 62 and 63 are or may be adapted to support 50 terminal lugs 65 and 66 to which circuit leads from the motor or other device to be controlled may be connected.

The switch operating mechanism is preferably disposed beyond the main switch casing and in a separate casing 70 disposed in front of and secured to the front wall of the main switch casing 10. Said casing 70 is or may be provided with a front cover plate 71 which may be secured to the casing in 55 any suitable manner as by the screws 72.

The switch operating mechanism includes an actuating electro-magnet having the U-shaped laminated magnet frame 75. Angle irons 76 are secured to opposite sides of the 60 upper leg of said frame and may serve as

attaching means by which the magnet is or may be secured to the upper wall of the casing 70. A coil 77 which is adapted to be connected in shunt across one phase of the circuit to be controlled, is received on the 70 lower leg of the magnet frame.

The armature 78 of the electro-magnet is or may be formed of laminæ secured between side plates 79 which depend below said laminæ.

In accordance with this invention, said armature is arranged to be loosely pivotally supported and for this purpose, the upper end of said armature is or may be formed with the elongated and, preferably, arcuate 80 pivot slot 80 therein through which and said angle irons 76 of the electro-magnet 63 a pivot pin 81 is extended. The arrangement is or may be such that, when said electro-magnet is energized, said armature 78 is 85 moved to an attracted position in contact with both poles of the magnet, and, when the switch mechanism hereinafter to be described is actuated manually, said armature is adapted to pivot on the lower pole of the 90 electro-magnet; and said pivotal movement is permitted by reason of the slot 80 whereby to permit the operating mechanism to be locked releasably in switch-closed position.

The switch operating mechanism includes 95 the bell crank levers 84 which are supported in spaced relation loosely on the shaft 85 and between the depending arms 86 of a supporting frame which is secured to the top wall of the casing 70. A connecting rod 87 is received between the lower arms of said bell crank levers 84 and is pivoted on a pin 85^a 100 which extends between said arms. The end of said connecting rod 87 is or may be threaded adjustably in a block 88 which is 105 disposed between and pivotally supported on a pin 89 extended through the lower ends of the side plates 79 of the armature 78. With this arrangement, the bell crank lever will respond to movements of the armature 110 78. The upper arms of said bell crank levers 84 are pivotally connected with a link 90; and said link is pivotally connected with a depending arm 100 which is fixed to the extended end of the switch operating 115 shaft 40.

A pin 101 may be extended between the arms 86 of the supporting bracket for the bell crank levers and serve as a stop whereby to limit the switch-open position of said bell crank levers.

With this arrangement, when the electro-magnet is energized, the armature will be attracted and the toggle comprising the bell crank levers 84 and the link 90 will be actuated to close the switch. Said toggle is arranged to be moved to a position less than the on-center or over-shot position whereby the switch will move to open-circuit position when the electro-magnet is deenergized; and 130

said electro-magnet is adapted to be energized for so long as the switch is adapted to be maintained closed.

Normally said switch is adapted to be actuated by the electro-magnet. Means, however, are or may be provided by which the switch may be opened and closed manually upon failure of the electro-magnet for any reason. Said means may include the shaft 85 which is or may be provided with a squared-end 105 adapted removably to receive a key or other suitable instrument by which the shaft may be rotated; and said key may be inserted through a suitable opening formed in the front cover plate 71 of the casing 70. Said shaft is or may be formed or provided with an extension, as a pin 106, extended on opposite sides thereof and disposed between said bell crank levers 84. A pin 107 is extended between and connected to said bell crank levers and is adapted to be engaged by the opposite ends of said pin 106 for the purpose of actuating the switch operating mechanism manually. Said shaft 85 is adapted to be rotated in a counter-clockwise direction (Fig. 5) to cause one end of said pin 106 to engage said pin 107 and move the toggle comprising the upper arms of the bell crank levers and said link 90 into a somewhat over-shot position whereby to hold the switch releasably in switch-closed position. Means are or may be provided to hold said toggle in over-shot position and said means may include the pin 108 secured to said bell crank levers and movable in a slot 109 formed in said link 90; and said pin is adapted to engage the bottom wall of said slot whereby to restrict the movement of the toggle members. When said shaft 85 is rotated manually in a clockwise direction, the other end of said pin 106 is adapted to be moved into contact with said pin 107 carried by the bell crank levers and move said toggle over the on-center position thereof, whereby the spring 46 serves to move the switch members rapidly into open position regardless of the rate of movement and independent of said shaft 85. When the switch operating mechanism is operated manually to close the switch, the armature 78 is adapted to pivot about the lower pole of the magnet frame 75, whereby to permit the toggle to be moved to an over-shot position, and, in this position, the upper end of the armature will be spaced away from the upper pole of the magnet frame. If the coil 77 should become energized when the switch has been closed manually, said armature will be pulled against the poles of the magnet frame and thereby move the toggle across on-center position and, consequently, when said coil is de-energized, the switch will move to open position automatically.

The circuit through said actuating coil 77 is adapted initially to be completed by a re-

mote-disposed controlling switch whereby to close the switch and the switch is provided with means to maintain the circuit closed until it is interrupted by the remote-disposed controlling switch or by the tripping coils. Said means may include an auxiliary switch or circuit controller associated with the oil switch. Said auxiliary switch may comprise a resilient movable contact member 110 which may be secured to one of the conducting strips 27 of a movable switch member, as, for instance, the conducting strip of the middle movable switch member. Said strip 110 is or may be provided with a reflected portion 111 which is adapted to make contact when the switch is closed with a contact member 112 detachably carried by a conducting support 113, which support is or may be disposed in line with and insulated from the middle stationary switch member and secured to said insulating plate 16 by the bolt 114 which forms a terminal member for the fixed contact member 112. Said resilient contact member 110 is or may be provided with an insulating block 114^a which is or may be secured removably to the end thereof; and said insulating block 114^a is adapted to be engaged and depressed by the movable member of the overload coils whereby to interrupt the circuit of the actuating coil 77, upon overload, and thereby effect the opening of the switch.

Said overload or tripping coils are or may be carried by a tripping frame illustrated more clearly in Figs. 11 and 12. Said tripping frame is or may be composed of a single flat strip of metal reflexed to form the integral top and bottom walls 115 and 116 respectively and the side connecting wall 117. Said top wall 115 is or may be formed with the upwardly extended ears 118 which are or may be secured to the front and rear walls of the main casing portion 10. Said frame is or may be disposed on the casing with the top wall 115 disposed substantially in line with the insulating plate 16 whereby to complete the closure for the oil receptacle. Said connecting wall 117 may be formed with the rearwardly extended ears 119 for a purpose not connected with this invention. Said lower wall 116 is adapted to support the tripping coils 120 two of which are here shown. Said tripping coils 120 may include center tubes 121 which are or may be of insulating material. Said tubes are preferably slidably received in apertures 122 of said lower wall 116 and the upper ends of said tubes are or may be secured to the upper wall 115 in a suitable manner, as by the screws 123. With this arrangement, the tripping coils may be removed from position by removing the screws 123 and withdrawing the tubes 121 downwardly out of the tripping coils and free from the supporting frame. Plungers 125 are or may be movably received in said

cores 121 and may be provided with suitable retardation devices whereby to delay the operation of the tripping coils. Said plungers are adapted normally to rest upon and be supported by a plate 126 which is disposed beneath both plungers. Said plate is or may be carried by a vertically-extended arm 127, which latter is slidably received and guided for vertical movement in slots 128 formed in the top and bottom walls 115 and 116 of the supporting frame. Said plate 126 is adapted to be adjusted vertically and clamped by suitable means (not necessary to describe herewith) whereby to vary the current setting of the tripping coils. Said coils are adapted separately and also conjointly to operate a U-shaped tripping frame 130, which is or may be pivoted to depending ears 131 formed preferably integrally with the bottom wall 116. Said tripping frame is or may be formed with arms 132 which are disposed above and are adapted to be engaged by striking discs 133 carried by the plungers of said tripping coils, whereby to actuate said tripping frame. Said tripping frame is adapted to engage the insulating block 114^a carried by the resilient contact member 110 included in the actuating coil circuit and depress said contact member from engagement with its cooperating stationary contact member whereby to interrupt the circuit through the actuating coil and thereby effect the opening of the switch.

Said mechanism-containing casing 70 is or may be provided with ventilating means whereby to facilitate the cooling of the actuating coil. Said ventilating means may include one or more openings 140 disposed in the bottom wall of said casing 70 beneath the actuating coil. The side walls of said casing 70 may be provided at one or both ends with one or more openings 141 in the upper portion thereof. The arrangement of said openings is or may be such that a draft through said casing and about said actuating coil is set up due to the heating thereof, whereby to promote the cooling of said coil.

Fig. 8 is a diagram of the control circuits of the switch. The remote control switch may include a circuit-closing switch 150 which is adapted to be momentarily depressed to close its circuit, whereby to effect the closing of the switch; and a circuit-opening switch 151 which is adapted to be momentarily depressed whereby to interrupt its circuit and effect the opening of the switch.

The circuit connections are or may be so arranged that when said circuit-closing switch 150 is depressed, a circuit is completed through said actuating coil 77 and the circuit-opening switch 151 between two phases of the line circuit. The oil switch is then closed by said coil 77 and the contact member 110 is moved, by the closing of the oil switch, into contact with its cooperating con-

tact member 112 whereby to shunt said circuit-closing switch 150 and maintain the circuit complete through said actuating coil 77 whereby to maintain the switch closed. When the circuit-opening switch 151 is depressed, the circuit through said actuating coil 77 is interrupted and the actuating coil is de-energized and the oil switch is consequently moved to open position and the auxiliary contact members which control the actuating coil 75 are separated whereby to maintain the circuit of the actuating coil interrupted until the remote circuit-closing switch 150 is again actuated.

Upon overload, said tripping coils act to separate the auxiliary contact members, whereby to de-energize the actuating and holding coil 77 and effect the opening of the switch; and the remote circuit-closing switch 150 must then be depressed to effect the reclosing of the switch.

An indicating member, as the plate 160, may be secured to the end of the operating shaft 40 and bear suitable indicia thereon which may be visible through a suitable aperture in the front cover plate of the casing 70 to indicate the closed or open condition of the switch.

It is obvious that the construction may be otherwise modified without departing from the spirit of the invention.

I claim:

1. An electric switch having the combination of a supporting plate, a supporting bracket carried by said plate and having depending arms, a bolt passed through said bracket and plate whereby to connect said bracket with said plate, said bolt having a head disposed between said arms and adapted to be held against rotation by said arms, a channel member pivotally connected with said arms, a brush member carried by said channel member, and a flexible conductor connected electrically with said brush member and the head of said bolt.

2. An electric switch having the combination of a movable switch member comprising two contact members, and a stationary switch member comprising a depending supporting plate, a separate stationary contact member for each movable contact member disposed on opposite sides of and bearing against said plate, and a common connecting means for both stationary contact members passed through both contact members and said plate and arranged to secure said contact members detachably to said support.

3. An electric switch having the combination of a movable switch member comprising two contact members, and a stationary switch member comprising a support, separate stationary contact members for said movable contact members disposed on opposite sides of said support, and securing

means passed through both stationary contact members and said support.

4. An electric switch having relatively movable switch members, operating mechanism therefor, electrically-operated means for actuating said operating mechanism, and manually-operated means for actuating said operating mechanism to close and open the switch, said manually-operated means having lost-motion connection with said operating mechanism.

5. An electric switch comprising the combination of a supporting plate, a movable switch member disposed below and pivotally supported by said plate, an operating shaft rotatably supported above said plate, a connecting rod extended through said plate and connected with said operating shaft and movable switch member, a spring encircling said connecting rod arranged to bear against said supporting plate and bias the switch toward open position, operating mechanism including toggle members connected with said operating shaft, and manually-operable means to actuate said toggle members to open and close the switch, said manually-operable means having lost motion connection with said toggle members and arranged to move said toggle to an over-shot position, whereby releasably to hold the switch closed, and break the toggle whereby to effect the opening movement of the switch independently of a corresponding movement of said manually-operable means.

6. An electric switch comprising the combination of a supporting plate, a movable switch member disposed below and pivotally supported by said plate, an operating shaft rotatably supported above said plate, a connecting rod extended through said plate and connected with said operating shaft and movable switch member, a spring encircling said connecting rod arranged to bear against said supporting plate and bias the switch toward open position, operating mechanism including toggle members connected with said operating shaft, and manually-operable means to actuate said toggle members to open and close the switch, said manually-operable means having lost motion connection with said toggle members and arranged to move said toggle to an over-shot position, whereby releasably to hold the switch closed, and break the toggle whereby to effect the opening movement of the switch independently of a corresponding movement of said manually-operable means, and electrically-operated means connected with said toggle arranged to operate the switch independently of said manually-operable means.

7. An electric switch having the combination of a movable switch member, operating mechanism therefor including a toggle, and electrically-operated actuating means arranged when energized to straighten said

toggle and hold it in such position, whereby to close and hold closed the switch, and release said toggle when de-energized, whereby to permit said toggle to open and effect the opening of the switch.

8. An electric switch having the combination of a movable switch member, operating mechanism therefor including a toggle, electrically operated means arranged to move said toggle to less than an on-center position whereby to close the switch, and hold said toggle in such position to maintain the switch closed, and manually-operated means arranged to move the toggle to an overshot position whereby releasably to lock the switch closed.

9. An electric switch having the combination of a movable switch member, operating mechanism therefor including a toggle, electrically operated means arranged to move said toggle to less than an on-center position whereby to close the switch, and hold said toggle in such position to maintain the switch closed, and manually-operated means arranged to move the toggle to an over-shot position whereby releasably to lock the switch closed, said manually-operated means also arranged to break said toggle whereby to permit the switch to move to open position.

10. An electric switch having the combination of a movable switch member, operating mechanism therefor including a toggle, electrically operated means for said toggle including an electro-magnet, a movable member connected with said toggle and governed by said electro-magnet to actuate said toggle and hold it in actuated position to hold the switch closed, and also governed by said electro-magnet to release said toggle and effect the opening of the switch.

11. An electric switch having the combination of a movable switch member, operating mechanism therefor including a toggle, electrically operated means for said toggle including a holding coil, a movable member connected with said toggle and governed by said coil, said mechanism and coil arranged to hold the switch closed while said coil is energized and effect the opening of the switch upon de-energization of said coil.

12. An electric switch having the combination of a movable switch member, operating mechanism therefor including a link associated with said switch member, a bell-crank lever pivotally connected with said link and arranged to form a toggle therewith, and electrically-operated actuating means for said operating mechanism including an electro-magnet, and an armature therefor connected with said bell-crank lever.

13. An electric switch having the combination of a movable switch member, operating mechanism therefor including a link associated with said switch member, a bell-crank

lever pivotally connected with said link and arranged to form a toggle therewith, and electrically-operated actuating means for said operating mechanism including an electro-magnet, an armature therefor, and a link pivotally connecting said armature and bell-crank lever.

14. An electric switch having the combination of a movable switch member, operating mechanism therefor including a link associated with said switch member, a bell-crank lever pivotally connected with said link and arranged to form a toggle therewith, and electrically-operated actuating means for said operating mechanism including an electro-magnet, a loosely pivoted armature therefor, and a link connecting said armature and bell-crank lever.

15. An electric switch having the combination of a movable switch member, operating mechanism therefor including a link associated with said switch member, a bell-crank lever pivotally connected with said link and arranged to form a toggle therewith, and electrically-operated actuating means for said operating mechanism including an electro-magnet, an armature therefor, a link pivoted to said bell-crank lever, and means adjustably connecting said link with said armature.

16. An electric switch having the combination of a movable switch member, operating mechanism therefor including a link associated with said switch member, a bell-crank lever pivotally connected with said link and arranged to form a toggle therewith, and electrically-operated actuating means for said operating mechanism including an electro-magnet, an armature therefor, a link pivoted to said bell-crank lever, and means adjustably connecting said link with said armature, said means comprising a block pivotally supported by said armature and having adjustable screw-threaded connection with said link.

17. An electric switch having the combination of a movable switch member, operating mechanism therefor including a link associated with said switch member, a bell-crank lever pivotally connected with said link and arranged to form a toggle therewith, and electrically-operated actuating means for said operating mechanism including an electro-magnet, an armature disposed adjacent the poles of said electro-magnet, and having one end extended beyond one of the poles thereof, means arranged pivotally to support the other end of said armature loosely adjacent the other pole of said electro-magnet, and a link connecting the extended end of said armature and said bell-crank lever.

18. An electric switch having the combination of a movable switch member, operating mechanism therefor including a link asso-

ciated with said switch member, a bell-crank lever pivotally connected with said link and arranged to form a toggle therewith, and electrically-operated actuating means for said operating mechanism including an electro-magnet, an armature disposed adjacent the poles of said electro-magnet and having one end extended beyond one of the poles thereof, means arranged pivotally to support the other end of said armature loosely adjacent the other pole of said electro-magnet, and permit that end thereof to move on its pivotal support toward and away from the electro-magnet, and a link connecting the extended end of said armature and said bell-crank lever.

19. An electric switch having the combination of a movable switch member, operating mechanism therefor including a link associated with said switch member, a bell-crank lever pivotally connected with said link and arranged to form a toggle therewith, and electrically-operated actuating means for said operating mechanism including an electro-magnet, an armature disposed adjacent the poles of said electro-magnet and having one end extended beyond one of the poles thereof, means arranged pivotally to support the other end of said armature loosely adjacent the other pole of said electro-magnet, and permit that end thereof to move on its pivotal support toward and away from the electro-magnet, a link pivoted to said bell-crank lever and said armature, and means connecting said link adjustably with said armature, said means comprising a block pivotally supported by the extended end of said armature and having adjustable screw-threaded connection with said link.

20. An electric switch having the combination of a movable switch member, operating mechanism therefor including an operating shaft connected with said switch member, a link pivotally connected with said shaft, a bell-crank lever pivotally connected with said link and arranged to form a toggle therewith, and electrically-operated actuating means for said operating means including a holding electro-magnet, and an armature therefor connected with said bell-crank lever, said electro-magnet arranged to be energized to hold said toggle and the switch closed, and release said toggle and permit the switch to open when de-energized.

21. An electric switch having the combination of a movable switch member, operating mechanism therefor including a link associated with said movable switch member, a lever pivotally connected with said link arranged to form a toggle therewith, a manually-operable shaft on which said lever is supported, and means connecting said shaft and lever arranged to move the toggle to an over-shot position whereby releasably

to hold the switch closed, and break said toggle whereby to effect the opening of the switch.

22. An electric switch having the combination of a movable switch member, operating mechanism therefor including a link associated with said movable switch member, a lever pivotally connected with said link and arranged to form a toggle therewith, a manually-operable shaft on which said lever is loosely supported, and means loosely connecting said shaft and lever arranged to move the toggle to an over-shot position whereby releasably to hold the switch closed, and break the toggle whereby to permit the switch to open independently of a corresponding movement of said shaft.

23. An electric switch having the combination of a movable switch member, operating mechanism therefor including a link associated with said switch member, a bell-crank lever pivotally connected with said link and arranged to form a toggle therewith, a manually-operable shaft on which said bell-crank lever is loosely supported, said shaft having lost-motion connection with said bell-crank lever, and said shaft arranged to move the toggle to an over-shot position whereby releasably to hold the switch closed, and break the toggle whereby to permit the switch to open independently of a corresponding movement of said shaft, and electrically-operated means for said operating mechanism including a holding electro-magnet arranged to actuate said bell-crank lever and hold the switch closed while energized and release the operating mechanism and permit the switch to open when said magnet is de-energized.

24. An electric switch having the combination of a movable switch member, operating mechanism therefor including a toggle, electrically-actuated mechanism including a movable member connected with said toggle and having two fulcrums about which it may pivot, an electro-magnet arranged to pivot said movable member about one of said fulcrums to actuate said toggle, whereby to close the switch electrically, and manually-actuated means arranged to pivot said movable member about said other toggle, whereby to close the switch manually.

25. An electric switch having the combination of a movable switch member, operating mechanism therefor including a toggle, electrically-actuated mechanism for operating said toggle, whereby to close the switch, said electrically-actuated mechanism having an armature and two fulcrum supports therefor, and a connection between said armature and toggle, said armature arranged to pivot about one of said fulcrums and move said toggle into a position less than an on-center position and hold said toggle in such position during the energization of said electrically-actuated mechanism, whereby to hold the switch closed.

26. An electric switch having the combination of a movable switch member, operating mechanism therefor including pivoted links comprising toggle members, one of said links having a recess therein, and the other of said links having a projection arranged to enter said recess, whereby to hold said toggle in straightened position, and actuating mechanism for said toggle, whereby to operate it to close and open the switch.

27. An electric switch comprising the combination of a movable switch member, operating means therefor including a toggle, electrically-actuated, toggle-operating means including an electro-magnet, an armature therefor, a pivotal support for said armature and means connecting said armature and toggle, said electrically actuated, toggle-operating means having a lost-motion connection in it, and said means arranged to hold said toggle in set position whereby to hold the switch closed, and manually-actuated means to actuate said toggle, said manually-actuated means having a lost-motion connection between it and said toggle and arranged to move said toggle to an over-shot position, whereby releasably to hold the switch closed.

28. An electric switch having the combination of a movable switch member, operating mechanism therefor including a toggle, electrically-actuated mechanism for operating said toggle, manually-actuated mechanism for operating said toggle, both of said mechanisms having lost-motion connections arranged to permit said toggle to be moved manually to an over-shot position, whereby releasably to hold said switch closed, and permit the switch to be opened manually independently of a corresponding movement of said manually-actuated mechanism.

29. An electric switch having the combination of a movable switch member, operating mechanism therefor including a toggle, manually-actuated toggle-operating mechanism arranged to move the toggle to an over-shot position, whereby releasably to hold the switch closed, and electrically-actuated toggle-operating mechanism having means to move said toggle from said overshot position to a position in which the switch is free to open, and hold it in such a position during the energization of said electrically-actuated mechanism, whereby to hold the switch closed.

30. An electric switch having the combination of a movable switch member, operating mechanism therefor including a link connected with said switch member, a bell-crank lever pivotally connected with said link

- and arranged to form a toggle therewith, a manually-actuated rotatable shaft arranged loosely to support said bell-crank lever, said shaft having a projection extended therefrom adapted to engage a projection of said bell-crank lever, whereby to move said toggle to an over-shot position and close the switch, and move said toggle out of said over-shot position and permit the switch to open free from said shaft, electrically-actuated mechanism for said operating mechanism including an electro-magnet, an armature therefor having the upper end thereof loosely pivoted adjacent the upper poles of said electro-magnet, whereby that end of the armature is permitted movement toward and away from the upper pole of the electro-magnet, said armature having its lower end extended beyond the lower pole of said electro-magnet, said armature arranged to contact with both poles of said electro-magnet in the attracted position thereof, and a link pivotally connected with said bell-crank lever and the extended end of said armature, the arrangement being such that said armature can fulcrum about its pivotal support and also about the lower pole of said electro-magnet.
31. An electric switch having the combination of switch-operating mechanism, including an actuating electro-magnet, a circuit-controller governing the circuit of said electro-magnet, and a switch-tripping coil arranged to actuate said circuit-controller and effect the opening of the switch, said switch-operating mechanism also having means to operate said circuit-controller.
32. An electric switch having the combination of an enclosing casing, switch members, a circuit controller, and a switch-tripping coil all contained in said casing, switch-operating mechanism including an electro-magnet arranged to close the switch and hold it closed when energized and effect the opening of the switch when de-energized, said circuit controller arranged to govern the circuit of said electro-magnet, and said switch-tripping coil arranged to actuate said circuit-controller, whereby to effect the opening of the switch, said switch-operating mechanism also having means to operate said circuit-controller.
33. An electric switch having the combination of relatively movable switch-members, operating mechanism therefor including an electro-magnet arranged to close the switch and hold it closed when energized and effect the opening of the switch when de-energized, a circuit-controller for said electro-magnet, and a switch tripping coil arranged to govern said circuit controller and effect the de-energization of said electro-magnet, whereby to effect the opening of the switch, said switch-operating mechanism also having means to operate said circuit-controller.
34. An electric switch having the combination or relatively movable switch-members, operating mechanism therefore including an electro-magnet arranged to close the switch and hold it closed when energized and effect the opening of the switch when de-energized, a circuit controller actuated by said operating mechanism and arranged to govern said electro-magnet, and a tripping coil arranged to actuate said circuit controller, whereby to effect the opening of the switch, said switch-operating mechanism also having means to operate said circuit-controller. 70
35. An electric switch having the combination of a movable switch member, a co-operating fixed switch member therefor, an auxiliary switch having a movable member electrically connected and movable with said movable switch member, and a fixed switch member cooperating with said movable auxiliary switch member, switch operating mechanism including a holding electro-magnet governed by said auxiliary switch arranged to close the switch and hold it closed while energized and a switch-tripping coil arranged to actuate said movable auxiliary switch member whereby to de-energize said holding coil and effect the opening of the switch. 80
36. An electric switch having the combination of a movable switch member, a co-operating fixed switch member, an auxiliary switch comprising a flexible contact member carried by and electrically connected with said movable switch member, and a co-operating fixed contact member, switch operating mechanism including a holding electro-magnet governed by said auxiliary switch and arranged to close the switch and hold it closed when energized and a switch tripping coil arranged to flex said auxiliary flexible contact member away from contact with said co-operating auxiliary contact member, whereby to effect the opening of the switch. 85
37. An electric switch having the combination of a movable switch member, a fixed switch member cooperating therewith, a contact member carried by and connected electrically with said movable switch member, a contact member cooperating with the aforesaid contact member and insulated from said fixed switch member, and means to separate said contact members without actuating said switch members. 90
38. An electric switch having the combination of a movable switch member, a fixed switch member cooperating therewith, a contact member carried by and connected electrically with said movable switch member, a contact member cooperating with the aforesaid contact member and insulated from said fixed switch member, a holding coil governed by said contact member arranged to hold the switch closed when energized, and a trip coil arranged to separate said contact members. 100

and de-energize said holding coil, whereby to effect the opening of the switch.

39. An electric switch having the combination of a movable switch member, a fixed switch member cooperating therewith, a contact member carried by and connected electrically with said movable switch member, a contact member cooperating with the aforesaid contact member and insulated from said 10 fixed switch member, a holding coil governed by said contact member arranged to hold the switch closed when energized, and a plurality of trip coils having means independently and also conjointly to separate said contact 15 members and de-energize said holding coil, whereby to effect the opening of the switch.

40. An electric switch having the combination of a plurality of movable switch members, cooperating fixed switch members, 20 an auxiliary contact member carried by and connected electrically with one of said movable switch members, a fixed contact member cooperating therewith and insulated from said fixed switch members, switch operating mechanism including a holding coil governed 25

by said contact members and arranged to hold the switch closed when energized, and a trip coil arranged to separate said contact members and de-energize said holding coil, whereby to effect the opening of the switch. 30

41. An electric switch having the combination of a plurality of movable switch members, cooperating fixed switch members, an auxiliary contact member carried by and connected electrically with one of said movable switch members, a fixed contact member therewith and insulated from said fixed switch members, switch operating mechanism including a holding coil governed by 35 said contact members and arranged to hold the switch closed when energized, a plurality of trip coils, and a tripping frame actuated by said trip coil arranged to separate said contact members, whereby to de-energize said holding coil and effect the opening of 40 the switch.

In testimony whereof, I have signed my name to this specification.

GEORGE W. O'KEEFFE.
